CONTAINER

Filed July 15, 1927

INVENTOR:
WALTER S. GRANT.

By *James S. Hopkins*,
ATTORNEY

UNITED STATES PATENT OFFICE.

WALTER S. GRANT, OF ST. LOUIS, MISSOURI.

CONTAINER.

Application filed July 15, 1927. Serial No. 205,880.

My invention relates to improvements in containers, and its particular object is to provide a container which (a) may be shipped, filled with contents, without crating, and (b) complies with Interstate Commerce Commission requirements as to sustaining a 4-foot drop without leakage, and (c) is capable of having its carrying handle and closure cap locked and sealed together for shipment.

10 The container of my invention consists of a drum-shaped body, having a hinged carrying-handle countersunk in its peripheral wall; a folding foot also countersunk in said peripheral wall; and a telescopic pouring spout 15 mounted through an annular depression in said peripheral wall; a screw-threaded collar fixed in said depression; a cap forming a closure for said collar; and a locking bar mounted on the flat face of said cap, with 20 means for locking and sealing said locking bar and said hinged carrying handle together.

By the construction thus outlined, the containers when ready (filled or empty) for shipment may be compactly loaded in the transportation vehicle, and have no projections—as to spout, handle, or supporting leg—to injure the vehicle or other freight, or the persons of the freight handlers.

Other advantages of said container will appear from the appended description.

Drawings.

In the drawings—

Fig. 1 is a top plan view of a container embodying my invention.

Fig. 2 is a vertical mid-sectional view of the same, taken on the line 2—2 of Fig. 1.

Fig. 3 is a sectional view of a fragment of the peripheral wall of said container, taken on the line 3—3 of Fig. 1.

Description.

The drum A comprises the heads 4—4 and peripheral wall B.

45 A folding leg 5 is hingedly mounted in the countersink 6, contoured in the wall B to receive the leg 5 in folded position, flush with the plane of the wall B.

50 Similarly the carrying handle 7 folds beneath the plane of said wall B, fitting into countersinks 8—8 and the truncated-conoidal cupped depression 9, formed at the top of the container, as shown in Figs. 1 and 2.

Within the cupped depression 9 is mounted a screw-threaded collar 10 having a closure 55 cap 11, which cap 11 is provided with a locking bar 12 having the perforated ears 13—13 projecting beyond the periphery of the cap 11, as shown in Figs. 1 and 2.

Toward the bottom of the drum A a counter-balancing weight 14 is mounted on the inner face of the wall B, to maintain the drum A in upright position when the leg 5 is extended as shown in Fig. 2.

A pouring spout 15 telescopes within the 65 collar 10. At the inner mouth of the radial spout 15, and partially closing said mouth, is a baffle-plate 16, through which the outer end of the vent tube 17 is mounted as shown in Fig. 2, the function of said baffle-plate 16 and 70 vent tube 17 being to prevent gurgling as the contents of the drum A are poured out.

The bottom of the depression 9 serves to catch any drippings from the spout 15 after each pouring operation. Pouring is accomplished by tilting the drum A upon its wall B.

Various modifications of structure may be made, departing from the form illustrated and described, without departure from my actual invention as defined in the appended 80 claims.

I claim:

1. A container comprising a drum having a peripheral wall, and a pouring spout radially and telescopically mounted in said wall, said 85 drum having a folding carrying handle and a folding leg, each arranged to lie within the plane of the peripheral wall of said drum when in folded position.

2. A container comprising a drum having a 90 peripheral wall; a pouring spout telescopically mounted in said wall and arranged to be locked in unextended position within the plane of said wall; a handle foldably mounted in said wall and arranged to be locked in 95 folded position within the plane of said wall; and a supporting leg hingedly mounted in a countersink in said wall and arranged to be seated within the plane of said wall when in folded position.

100 In testimony whereof I have hereunto affixed my signature.

WALTER S. GRANT.
